(57) **CLAIM**

The ornamental design for an armature for glue application, as shown and described.

DESCRIPTION

FIG. 1 is a front perspective view of an armature for glue application showing my new design, showing a short version of an armature;

FIG. 2 is a rear perspective view thereof;

FIG. 3 is a side elevational view thereof;

FIG. 4 is a rear elevational view thereof;

FIG. 5 is a front elevational view thereof;

FIG. 6 is a front perspective view of second embodiment of an armature for glue application, showing a long version of an armature;

FIG. 7 is a rear perspective view of FIG. 6;

FIG. 8 is a side elevational view of FIG. 6;

FIG. 9 is a rear elevational view of FIG. 6; and,

FIG. 10 is a front elevational view of FIG. 6.
